CLAIM

The ornamental design for a medical infusion pump, as shown and described.

DESCRIPTION

FIG. 1 is a front, top, and right side perspective view of a medical infusion pump showing our new design;

FIG. 2 is a front elevational view thereof;

FIG. 3 is a rear elevational view;

FIG. 4 is a top plan view thereof;

FIG. 5 is a bottom plan view thereof;

FIG. 6 right side elevational view thereof;

FIG. 7 is a left side elevational view;

FIG. 8 is a rear, top, and right side perspective view thereof;

FIG. 9 is a rear, top, and left side perspective view thereof;

FIG. 10 is a front, top, and left side perspective view thereof;

FIG. 11 is a front, bottom, right side perspective view thereof;

FIG. 12 is a rear, bottom, right side perspective view thereof;

FIG. 13 is a rear, bottom, left side perspective view thereof; and,

FIG. 14 is a front, bottom, left side perspective view thereof.

The broken lines in the drawings depict portions of the medical infusion pump that form no part of the claimed design.
